UNITED STATES PATENT OFFICE.

CHARLES W. CONGER, OF THE DALLES, OREGON.

ELECTRIC LANTERN.

1,277,549.

Specification of Letters Patent.

Patented Sept. 3, 1918.

Application filed August 13, 1917. Serial No. 186,014.

To all whom it may concern:

Be it known that I, CHARLES W. CONGER, a citizen of the United States, residing at The Dalles, in the county of Wasco, State of Oregon, have invented certain new and useful Improvements in Electric Lanterns; and I do hereby declare the following to be a full, clear, and exact description of the invention, such as will enable others skilled in the art 10 to which it appertains to make and use the same.

This invention relates to electric lanterns, and has for an object to provide an electric lantern of improved, simple and inexpensive 15 construction, the parts thereof being so arranged that the rays from the lamp contained therein will be reflected directly upon the ground.

With the above and other objects of similar nature in view, the invention consists in the construction, combination and arrangement of parts set forth in and falling within the scope of the appended claim.

In the drawing:

Figure 1 is a side elevation of a lantern constructed in accordance with the invention,

Fig. 2 is a bottom plan view thereof,

Fig. 3 is a central vertical sectional view, 30 and

Fig. 4 is a transverse section taken on the line 4—4 of Fig. 3, the battery being removed.

Referring now more particularly to the 35 accompanying drawing, there is shown an electric lantern, such as contemplated by the invention, consisting of a skeleton base 5 including a circular bottom ring 6, and equidistantly spaced pairs of uprights 7, each 40 pair of said uprights being preferably formed from a single length of relatively heavy wire that is bent into substantially U-shape, and embraces diametrically opposite points of the ring 6 at the junction of its 45 arms with its connecting bight portion 8. Said bight portions 8 of the wires extend diametrically of the ring 6 and cross each other at approximately the center of the latter while supported thereon at their point 50 of crossing is a socket 9 in which an electric lamp 10 is removably disposed. Supported by the uprights 7 at their upper extremities

is a receptacle 11 in which is contained a battery 12.

Leading downwardly from the receptacle 55 11 along opposed uprights 7 and bent to extend into the socket 9 are tubes 13, while mounted upon the side of the receptacle is a slide switch 14 adapted to engage the terminals 15 and 16 to close the circuit, the 60 switch being normally disengaged from the terminal 15 whereby the circuit is open. A wire 17 leads from one pole of the battery 12 to the terminal 15 of the switch while a second wire 18 leads from the other terminal 16 65 and through one of the tubes 13 to the socket 9. A third wire 19 leads from the socket 9 through the other tube 13 and thereon to the other pole of the battery. Thus the battery 12, lamp 10 and socket 9 are connected in circuit so that by operating the 70 switch the lamp is controlled as is evident.

It will be noted that the bottom 20 of the receptacle 11 is disposed above the lamp 10 and when suitably polished or otherwise 75 treated provides an efficient reflector through the medium of which the light rays from the lamp 10 are deflected downwardly onto the ground.

The person carrying the lantern will not 80 become blinded by the light shining into his eyes as is the case with lanterns of other types, while the surface which he is traversing will be effectually illuminated. The receptacle 11 is equipped with a top 20' removably held in place by means of spring 85 fasteners 21 while there is also provided for carrying the lantern a bail 22 that is pivotally carried by arm 23 secured to the side of the receptacle, there being mounted on 90 said arms slides 24 and provided on the bail ends extensions 25 that are engaged by the 95 slides so as to maintain the bail in rigid relation to the receptacle to prevent swinging of the latter as it is carried.

What I claim is:

An electric lantern, comprising a base formed from a circular bottom ring, U-shaped frames disposed in crossed relation to each other to form uprights and having 100 bights at their closed ends to embrace the ring, a lamp socket fixed to the frame at the crossed portions thereof, a receptacle supported by the uprights at a point elevated

- above the socket, tubes extending from the socket upwardly into the receptacle, a battery within the receptacle, wires leading from the battery to socket and trained through the tubes to form an open circuit, and a switch exteriorly on the receptacle to close the circuit.

In testimony whereof I affix my signature in the presence of two witnesses.

CHARLES W. CONGER.
